UNITED STATES PATENT OFFICE.

HENRY J. HASSENFELD, OF PROVIDENCE, RHODE ISLAND.

PENCIL SHARPENER.

Application filed March 11, 1925. Serial No. 14,634.

My invention relates to pencil sharpeners of that type which comprises a conical sharpening socket and is rotatable by the inter-engaging thumb and finger of the operator.

- 5 The essential objects of my invention is to avoid in the construction of my device the necessity of employing solder, electric welding, or screws, and thus secure a maximum of strength at a minimum cost.
- 10 To the above enumerated ends essentially, but not exclusively, my invention consists in such parts and in such combinations of parts as fall within the scope of the appended claim.

15 In the accompanying drawings which form a part of this specification—

Figure 1 is a side elevation of a sharpener embodying my invention,

20 Figure 2, a similar elevation of the same taken at an angle of 95 degrees from the showing in Figure 1, and

Figures 3 and 4, sections on line 3—3 and 4—4 respectively of Figure 1.

Like reference characters indicate like 25 parts throughout the views.

My device comprises a tubular member or body 6, integral with which is a conical socket or head 7 provided with a longitudinal slot 8 upon one of whose edges is formed 30 a lateral tongue 9 provided upon its top and bottom with lugs 10. A knife blade 13 rests upon the tongue and its beveled lateral edge 14 extends into the slot 8. The blade is pro-

vided with rectangular cavities 15 in its top and bottom edges. The lugs 10 are bent and 35 forced by swaging or otherwise into the cavities 15 where they are tightly held by friction.

It will be observed that the described construction permits the formation of the parts 40 from initially flat metallic blanks. Further that the attachment of the blade by interlocking integral lugs not only insures a permanent and firm engagement of the blade, but avoids the expensive use of screws 45 and the costly process of welding.

I claim:—

As an improved article of manufacture a pencil sharpener composed of two elements only, a tubular body and a knife blade, the 50 body being formed with a tubular socket with longitudinal slot and an integral lateral tongue at one edge of the slot and provided at each end with a bendable lug, the lugs being bent to form knife blade engaging members 55 to form a passage for the insertion of the knife blade, and a knife blade insertible in a plane parallel with said flange to rest thereupon and having cavities at its ends into which the said lugs are bent, the 60 blade extended with its sharpened edge out of parallelism with the walls of the said slot.

In testimony whereof I have affixed my signature.

HENRY J. HASSENFELD.
